LINE INDICATOR AND AUTOMATIC BOTTOM MARGIN WARNING MECHANISM FOR A TYPEWRITER

Si-Ling Ts'ao, Shihlin, Taipei, Taiwan, China.

Application August 24, 1956, Serial No. 606,062

23 Claims. (Cl. 197—189)

This invention relates to typewriters, and more particularly to a line indicator and automatic bottom margin warning mechanism for a typewriter.

The main object of the invention is to provide a novel and improved line indicating and bottom margin warning mechanism for a typewriter, said mechanism involving simple components, being relatively compact in size, and being suitable for installation on a typewriter of conventional construction.

A further object of the invention is to provide an improved line indicator and bottom margin warning mechanism for a typewriter, said mechanism involving inexpensive parts, being durable in construction, and providing a continuous indication of the number of lines advanced on a sheet of paper in a typewriter, as well as providing an automatically operated audible warning when the last line to be written has been reached.

A still further object of the invention is to provide an improved line indicator and bottom margin warning mechanism for a typewriter, said mechanism being easy to set up for use, being automatically placed in operation responsive to the actuation of any of the letter keys, the shift key or the space bar of the typewriter, as desired by the typist, and being arranged so that it is automatically cleared for the initiation of a line counting operation by the act of placing a sheet of paper in the typewriter.

Further objects and advantages of the invention will become apparent from the following description and claims, and from the accompanying drawings, wherein:

Figure 1 is a fragmentary top plan view of the carriage portion of a typewriter provided with an improved line indicator and automatic bottom margin warning mechanism constructed in accordance with the present invention.

Figure 2 is a longitudinal vertical cross sectional view taken on the line 2—2 of Figure 1.

Figure 3 is a transverse vertical cross sectional view taken on the line 3—3 of Figure 1.

Figure 4 is a vertical cross sectional detail view taken on the line 4—4 of Figure 3.

Figure 5 is a transverse vertical cross sectional detail view taken on the line 5—5 of Figure 1.

Figure 6 is a fragmentary vertical cross sectional view taken substantially on the line 6—6 of Figure 1 and showing the connection of the space bar to the associated portions of the automatic line indicator and warning mechanism of the present invention.

Figure 7 is a fragmentary rear elevational view of the mechanism taken on the line 7—7 of Figure 6.

Figure 8 is a horizontal cross sectional view taken on the line 8—8 of Figure 7.

Figure 9 is a fragmentary transverse vertical cross sectional view taken on the line 9—9 of Figure 7, and showing the connection of the shift key of the typewriter to the associated portions of the automatic line indicator and warning mechanism of the present invention.

Figure 10 is a vertical cross sectional detail view taken on the line 10—10 of Figure 8, showing a typewriter ele-

2

ment which is actuated responsive to the operation of any of the letter keys of the typewriter and which is associated with the automatic line indicator and warning mechanism of the present invention illustrated in the preceding views.

5 Figure 11 is a vertical cross sectional detail view taken substantially on the line 11—11 of Figure 1, and showing the warning bell and the associated operating mechanism therefor, forming part of the present invention.

Figure 12 is an enlarged transverse vertical cross sectional detail view taken on the line 12—12 of Figure 1.

Referring to the drawings, 20 generally designates a typewriter of generally conventional construction provided with the usual movable carriage 21 on which is mounted the cylindrical platen member 22, which may be

15 in the form of an elongated rubber roller. Associated with the roller 22 is the conventional paper holding mechanism which is provided with a release lever 23 carried at the end of an arm 23' pivoted adjacent the right end of the roller 22, as viewed in Figure 1. The lever 23 is movable upwardly and forwardly, for releasing the mechanism associated therewith for the purpose of inserting a sheet of paper in the typewriter, namely, around the roller 22.

Rigidly secured to the carriage 21 at the right end thereof is a rearwardly extending arm 24, the roller shaft extending through the forward portion of said arm and being provided thereon with the adjusting knob 25, whereby the roller 22 may be manually rotated from the right end thereof, as viewed in Figure 1. A rearwardly extending arm 26 is secured to the left end of the carriage for a purpose presently to be described.

The left end of the roller 22, as viewed in Figure 1, is provided with a ratchet wheel 27 which is engaged in a conventional manner by the pawl element associated

35 with the line space lever 28 to rotate roller 22 responsive to the actuation of the line space lever 28 by the typist as the typist reaches the end of a line and wishes to start a new line. As is well understood, the operation of the lever 28 returns the carriage for starting the new line and also rotates the roller 22 to provide the required line spacing. The line spacing is determined in accordance with the setting of the conventional line spacing adjusting lever 29, which may be set to provide either single spacing, double spacing, or triple spacing, as desired.

40 Pivoted to the carriage parallel to and forwardly adjacent the roller 22 is the paper bail 30, provided with the rubber paper gripping sleeves 31. The carriage is provided with the conventional margin setting and letter 50 counting scale 32, located immediately to the rear of the roller 22.

The left end of the shaft of roller 22, as viewed in Figure 1, is provided with a knob 33, and with a relatively large sprocket wheel 34 secured on the roller shaft 35 adjacent said knob 33, as shown in Figure 1. The left end portion of the roller shaft is designated at 35 in Figure 3, and the sprocket wheel 34 is rigidly secured on the roller shaft 35 so as to rotate simultaneously therewith.

60 Secured to the arm 26 rearwardly of and parallel to roller shaft 35 is an auxiliary shaft 36 on which is rotatably mounted a relatively small sprocket wheel 37 which is in alignment with the sprocket wheel 34 and which is coupled to sprocket wheel 34 by a sprocket chain 38.

65 Rigidly secured to the sprocket wheel 37 is a relatively large gear 39 which meshes with a relatively small gear 40 rigidly secured on a feed screw 41 journaled in the arms 26 and 24 rearwardly of and parallel to the roller 22. A bracket member 42 is rigidly secured to arm 26 and is formed with a transversely extending horizontal shaft portion 43 on which is journaled a supporting roller 44. Designated at 45 is a flexible tape which engages over the

roller 44 and which is secured at one end thereof to a spring-biased reel member 46 contained in a drum-like housing 47 rigidly secured in any suitable manner to the frame of carriage 21 subjacent the feed screw 41, as shown in Figure 4, the reel 46 being rotatably mounted on a stationary shaft 48 provided centrally in the housing 47 and containing a spiral spring 49. As shown in Figure 4, the inner end of the spring 49 is secured to the shaft 48 and the outer end of said spring is secured to the peripheral wall of reel 46. The tape 45 is secured to the periphery of the reel 46, whereby the spring 49 acts to wind up the tape on the reel 46 under the tension provided by the spiral spring 49.

Designated at 50 is a pointer element which is rigidly secured in any suitable manner to the bracket 42 in a position parallel to the shaft element 43 but with its tip located adjacent the edge of the tape 45, as shown in Figure 1.

The outer end of tape 45 is secured to the block member 51 slidably mounted on the feed screw 41, said block being formed with the horizontal bore 52 through which the feed screw 41 extends, as shown in Figure 12.

Designated at 53 is a plate member which is provided at its opposite ends with shaft elements 54 and 55, said shaft elements being pivotally supported in the respective arms 24 and 26, whereby the plate member 53 is pivoted for rotation on an axis parallel to the feed screw 41 and is located rearwardly adjacent said feed screw, as shown in Figure 1. The plate member 53 is provided with a widened top portion, such as the flange or head 54', on which is inscribed a line margin setting scale 56, comprising evenly spaced calibrations corresponding to the number of lines of typewritten material which may be placed on a single sheet of typewriting paper. The tape 45 is calibrated with a similar scale.

As shown, the plate member 53 extends substantially vertically and is formed with a longitudinal slot 57 which extends for the major portion of its length, as shown in Figure 2. A rearwardly extending guide pin 58 is secured to the rear surface of the block 51 and extends slidably through the guide slot 57, supporting the block 51 for longitudinal movement parallel to the plate 53.

Secured to the rear marginal portion of the block 51, as by a machine screw 59, is a generally horizontal leaf spring 60 on which is rigidly secured an upstanding lug 61 which extends loosely through a vertical bore 62 formed in the block 51 and communicating with the bore 52. The lug 61 is shaped to at times engage between adjacent threads of the screw 41, as shown in Figure 12, whereby the block 51 will be moved longitudinally responsive to rotation of screw 41. Spring 60 biases the lug 61 upwardly in the bore 62 towards its thread-interengaging position, as shown in Figure 12.

Designated at 63 is a depending leaf spring secured at its upper portion to the upper marginal portion of the front surface of block 51, as by a machine screw 64. The leaf spring 63 is provided with an intermediate, downwardly and forwardly offset portion 65 and a terminating vertical portion 66 which is parallel to but forwardly offset from the upper portion of the leaf spring 63, as shown in Figure 12.

As shown in Figure 12, the lower marginal portion of the vertical upper element of leaf spring 63 is engageable with the edge of the horizontal leaf spring 60 when the lug 61 is in thread-interengaging position, and under these conditions, the leaf spring 63 has no effect. However, if the leaf spring 60 is slightly depressed so that its free outer edge engages the inclined portion 65 of leaf spring 63, leaf spring 63 is effective to depress the free outer portion of leaf spring 60 and to hold the lug 61 in lowered position, disengaged from the feed screw 41. This will continue until the leaf spring 63 is flexed outwardly, which is accomplished, at times, by rotation of the plate member 53, as will be presently described, said plate member 53 being provided with a forwardly extending arm 67 which

is engageable with the depending lower portion 66 of leaf spring 63 to flex the leaf spring 63 forwardly, away from the edge of the leaf spring 60, responsive to the clockwise rotation of plate member 53, as viewed in Figure 12, whereby to release leaf spring 60 from its downwardly flexed condition.

It will be understood that the bore 62 in the block 51 is of sufficient size to provide ample clearance for the projection 61 to allow said projection to angle in the bore as the spring 60 is flexed.

Designated at 68 is a vertical plunger element which is slidably mounted in the forward portion of the block member 51, the plunger 68 being provided with an enlarged top head 69 which is biased upwardly by a coiled spring 70 surrounding the upper portion of the plunger 68 and bearing between the top surface of the block 51 and the head 69. As shown in Figure 12, the lower end of plunger 68 rests on the leaf spring 60 but is normally ineffective to cause downward flexure of said leaf spring.

Designated at 71 is a longitudinally extending bar member which is disposed parallel to the feed screw 41 and which is rotatably supported on the shaft members 54 and 55 by arcuate arms 72 and 73 provided on the respective ends of the bar 71 and located inwardly adjacent the carriage arms 24 and 26.

The bar member 71 is located immediately above the head 69 of plunger 68 and is of sufficient weight to depress the plunger 68 and to flex leaf spring 60 downwardly. However, the bar 71 is normally supported in an elevated position by an arm 74 rigidly secured to the paper releasing lever 23, as shown in Figure 5, the arm 74 being in alignment with and underlying the end arm 72 of arm 71 and slidably engaging the bottom surface of arm 72. As will be apparent from Figure 5, when the lever element 23 is moved upwardly and forwardly, as is done when a sheet of paper is inserted in the typewriter, the arm 72 is released, allowing the bar 71 to move downwardly and to engage head 69. This causes plunger 68 to depress the leaf spring 60 and to cause the free end of said leaf spring 60 to lockingly engage beneath the downwardly and forwardly inclined intermediate portion 65 of leaf spring 63, whereby the lug 61 is held in a disengaged position with respect to the threads of feed screw 41. Thus, the block member 51 is automatically released from the threads of the feed screw when the paper release lever element 23 is pulled forwardly, namely, when a sheet of paper is inserted in the typewriter. When this occurs, the spring 49 associated with the tape 45 acts to move the block 51 toward the left end of the typewriter carriage.

As shown in Figure 12, a spacing washer or other suitable spacing element, designated at 75, is provided between the leaf spring 60 and the bottom surface of block member 51, providing a clearance space between the leaf spring and said bottom surface. A similar spacing washer or analogous element 76 is provided between the upper portion of leaf spring 63 and the front vertical surface of block member 51.

Designated generally at 77 is a stop member for limiting the movement of the block member 51 toward the right, said stop member 77 comprising a shaft element 78 which is engageable through the slot 57 and which is provided with a locking wing nut 79a clampingly engageable against the rear surface of plate member 53. The forward portion of the stop member 77 comprises a yoke having a relatively short top arm 79 and a substantially longer bottom arm 80 which projects forwardly a substantial distance from the feed screw 41 which is received between arms 79 and 80, as shown in Figure 5. The member 77 is suitably shouldered at 81 so that said member may be rigidly secured in adjusted position along the plate 53 by tightening the wing nut 79a.

The lower arm 80 is substantially in the same horizontal plane as the space between leaf spring 60 and the bottom surface of block member 51 and is substantially aligned therewith. Formed on the end portion of the lower arm

80 is a tapered wedge member 82 which is directed towards the space between the bottom surface of block member 51, and leaf spring 60 and which is engageable in said space when the block member reaches a position along feed screw 41 closely adjacent the stop member 77. As will be readily apparent, when the wedge member 82 engages between leaf spring 60 and the bottom surface of block member 51, the leaf spring 60 will be deflected downwardly and will engage with the inclined portion 65 of leaf spring 63, whereby the force of the leaf spring 63 will exert a camming action on the free forward end of leaf spring 60 and deflect said leaf spring 60 further downwardly, as well as retaining the leaf spring 60 in a downwardly flexed position. As above explained, this disengages the top end portion of lug 61 from between the threads of the feed screw 41, releasing the block member 51 and allowing the spiral spring 49 associated with the tape 45 to return the block member toward the left end of carriage 21.

The top of the block member 51 is provided with an abutment block element 84 underlying the head 69 of plunger 68, and limiting the downward movement of said plunger produced by the action of bar member 71 thereagainst when said bar member is released, as by the depression of the paper release lever element 23.

Mounted on the left end portion of the carriage 21 is a warning bell 85, said bell being secured on a transversely extending horizontal shaft element 86, as shown in Figure 1, located adjacent to the arm 26 and beneath the bar 71. A clapper arm 87 is pivoted at 88 to the typewriter carriage 21 and is provided with the clapper element 89 at one end thereof, received inside the bell 85 and biased against the inner peripheral wall surface of the bell by a coiled spring 90 connecting the opposite end portion of clapper arm 87 to the carriage 21.

As shown in Figure 11, the clapper arm 87 is provided at the end thereof opposite the clapper 89 with a laterally extending bracket element 92 having an obliquely extending extension 93 to the end of which is pivoted a triangular pawl element 94 whose tapered end extends into the path of movement of the block member 51. One end of the spring 90 is connected to the opposite end of the pawl element 94, as shown in Figure 11, biasing the pawl element counterclockwise into engagement with a lug 95 provided on the bracket member extension 93. The spring 90 thus acts to bias the wider portion of the pawl 94 against the lug 95, as well as to bias the clapper bar 87 in a clockwise direction, as viewed in Figure 11, namely, to bias the striking portion 89 of the clapper against the inside surface of the bell 85. When the block member 51 is released by engagement with the wedge-like element 82 on stop member 77, as above described, the tape biasing spring 49 returns the block member 51 toward the left end of the carriage, whereby the block member 51 engages the tapered end portion of the pawl element 94, rotating the clapper arm 87 counterclockwise, as viewed in Figure 11, until the block member 51 slips past the tapered end of the pawl member 94, whereupon spring 90 returns the clapper arm 87 clockwise, causing the striker element 89 to strike the bell 85 and provide an audible signal. The block member 51 is free to move to the right, as viewed in Figure 11, without producing any actuation of the bell 85, since the pawl element 94 is yieldable in a clockwise direction, as viewed in Figure 11, without causing any rotation of the clapper arm 87. Thus, an audible signal is provided each time the block member 51 travels toward the left end of the carriage 21 subsequent to the release of said block member by the wedge element 82 on stop member 77.

When the block member 51 is moved to its extreme left position, as viewed in Figure 1, by the action of spiral spring 49 on tape 45, subsequent to the disengagement of projection 61 from the threads of screw 41, the block member actuates the warning bell 85, as above described, and then comes to rest at a position wherein the pointer element 50 shows "zero" on tape 45, this position being established by the location of the left end of slot 57, since

said left end of slot 57 acts as a stop means to limit further leftward movement of pin member 58 in said slot, as viewed in Figures 1 and 2.

The gear ratios between sprocket wheel 34 and sprocket wheel 37, and gear 39 and pinion gear 40 are such as to provide a complete revolution of the feed screw 41 for rotation of platen roller 22 through an angle corresponding to a single line space. Thus, the block member 51 advances one thread for each single line space step of rotation of the palten roller 22. The tape 45 is calibrated so that each division on the tape corresponds to the spacing between two adjacent threads on the feed screw 41. The fixed scale 56 on the flange member 54 is calibrated in the same manner as the tape 45, so that the block member 51 may be set at a position corresponding to a desired number of line spaces from the top edge of the sheet of paper in beginning a letter or other piece of typewritten material by noting the position of the zero point on tape 45 with respect to the scale 56. Similarly, the operator may determine at any time the number of lines typed by reading the tape 45 at the pointer 50, making the proper deduction for the number of lines allowed at the top margin. The same information will be provided by observing the position of the zero point of tape 45 with respect to scale 56.

As mentioned above, the device is cleared for use by the act of operating the paper release lever member 23 in inserting a sheet of paper in the typewriter. When this occurs the block member 51 is retracted to its starting position by the action of the spring 49, the block member 51 being released, as above described, by the release of bar 71 and the action of said bar on the plunger 68, the plunger being depressed thereby, whereby projection 61 is disengaged from the threads of feed screw 41.

As will be readily apparent, under these conditions, the leaf spring 60 is retained in its downwardly flexed position by the engagement of its forward edge with the inclined retaining portion 65 of leaf spring 63. In order to set the line indicator into operation, it is necessary to free the leaf spring 60 so that the projection 61 may again ascend into engagement with the threads of feed screw 41. This is accomplished by causing plate 53 to rotate clockwise, as viewed in Figure 12, responsive to the operation of one of the normal operating elements of the typewriter, other than the paper release lever element 23. Any of the operating elements of the typewriter may be employed as the means for rotating the plate member 53 sufficiently to cause the arm 67 to engage the depending lower portion 66 of spring 63. As will be apparent from Figure 12, when the end of the arm 67 engages spring portion 66, the member 63 is flexed outwardly, allowing the spring 60 to return to its normal position, shown in Figure 12, wherein the top end of projection 61 is interengaged with the threads of feed screw 41.

In the embodiment of the invention illustrated in the drawings, means is provided whereby the operator may select either the typewriting key elements, the space bar, or the shift key of the typewriter as the means for initiating the operation of the line indicating and bottom margin warning device.

Rigidly secured to the back wall 100 of the typewriter frame and projecting rearwardly and horizontally therefrom are a pair of supporting arms 111, 111. Rotatably mounted in the ends of the arms 111, 111 and extending parallel to the typewriter rear wall 100 is a shaft 104 on which is secured an arm 105 formed at its top end with the rearwardly offset stop member 83 which engages the plate member 53, as shown in Figures 6 and 7. Rigidly secured to the intermediate portion of shaft 104 is an upstanding arm 103. Another upstanding arm 103 is rigidly secured to the end of shaft 104 opposite the arm 105. Rigidly secured to the top ends of the arms 103 are the respective horizontal, forwardly extending arms 102, 102. Slidably but non-rotatively mounted in the forward 70 end portions of the horizontal arms 102, 102 is a hori-

zontal rod member 101, extending parallel to the back wall 100 of the typewriter frame and located between said back wall and the rear rod 104, as shown in Figure 8.

Secured rigidly on one end of the rod member 101 is a cylindrical block member 121 formed at its bottom with four evenly spaced transversely extending grooves 122, 123, 124 and 125.

Extending rotatably through the intermediate portions of the arms 111, 111 is a horizontally extending rod member 126 having an arm 110 rigidly secured to the intermediate portion thereof, said arm extending upwardly and being engageable in any one of the grooves 122, 123, 124, and 125, depending upon the longitudinally adjusted position of the rod 101. The arm 110 is biased to an upstanding position wherein its top end is engageable in one of the grooves 122, 123, 124 or 125 by a coiled spring 113 connecting arm 110 to a rearwardly adjacent upstanding arm 105' secured on shaft 104.

As will be readily apparent, the arm 110 may be manually rotated to disengage its top end from the groove in the bottom of the member 121, whereby said member 121 may be shifted longitudinally by hand, if so desired.

Integrally formed with the longitudinally adjustable rod 101 are the forwardly divergent side arms 107, 107 which extend forwardly and horizontally and which are rigidly connected together by a horizontally extending bar member 106 disposed parallel to the rear wall 100 of the typewriter inside the typewriter housing. As shown, the arms 107 extend through a slot 129 formed in the rear wall 100 of the typewriter frame.

Rod member 106 has an end extension 130 which may be at times engaged with the hook-like member 131 forming part of the conventional existing shift key mechanism, illustrated in Figure 9, wherein the typewriter shift key is shown at 132. As is illustrated in Figure 9, the shift key mechanism terminates in an upstanding serrated element 134 and the bar member 106 is located on an axis just within the corner defined between the upstanding element 134 and the remainder 135 of the link member 131 on which member 134 is formed. Thus, the end 130 of bar member 106 may be at times engaged in said corner by suitably adjusting the rod 101. Such engagement may be accomplished by setting rod member 101 so that the top end of arm 110 engages in the notch 122. Under these conditions, when the shift key 132 is depressed, the link member 135 is moved forwardly, as viewed in Figure 9, moving the bar member 106 forwardly, and thereby causing shaft 104 to be rotated counterclockwise, as viewed in Figure 6, which in turn causes stop arm 83 to act against the plate member 53 and rotate said plate member clockwise. The clockwise movement of plate member 53 causes arm 67 to engage against the depending lower portion 66 of leaf spring 63, flexing the leaf spring outwardly and releasing the leaf spring 60, if said leaf spring 60 has become engaged with the inclined retaining portion 65 of leaf spring 63.

Thus, the device may be set so that the line indicating and bottom margin warning mechanism is set into operation responsive to the depression of shift key 132. This is done by adjusting the rod member 101 manually so that the top end of arm 110 engages in the first groove 122.

Designated at 136 is a conventional element, already existing in the typewriter which is located within the typewriter housing forwardly of the rear wall 100, as shown in Figure 6. Member 136 represents any one of a number of elements of the typewriter which rotate responsive to the depression of any of the letter keys of the typewriter.

Rigidly secured to the member 136 is a rearwardly extending arm 137 formed at its rear end with a depending lug 114. Secured on the bar member 106 is an upstanding pin 108 which is engageable by the lug 114 when the bar member is adjusted to the position thereof shown in Figures 7 and 8, namely, wherein the top end of arm

110 engages in the second transverse bottom groove 123 of member 121. As shown in Figure 6, the arm 137 is connected to the lower portion of the member 136, and the member 136 rotates clockwise, as viewed in Figure 6, responsive to depression of any of the typewriter letter keys, whereby the rod 101 is moved forwardly, causing shaft 104 to rotate counterclockwise, as viewed in Figure 6. The stop member 83 acts against the plate member 53 to rotate said plate member clockwise, as viewed in Figure 6, and to cause arm 67 to flex leaf spring 63 outwardly, releasing leaf spring 60, and initiating the operation of the line indicating and bottom margin warning mechanism.

Rigidly secured to bar member 106 is a depending lug 138, located opposite the upstanding lug 108, the depending lug 138 being at times engageable by an upstanding lug 115 formed on the end of the link member 139 connected to the space bar mechanism of the typewriter and arranged to move forwardly responsive to the depression of the space bar, as shown at 140. As shown in Figure 8, the link member 139 is laterally spaced from the member 137 by a distance equal to the spacing between the bottom groove 123 and the bottom groove 125 of member 121. Thus, by adjusting the rod 101 to a position wherein the top end of arm 110 engages in bottom groove 125, the lug 138 is placed in a position to be engaged by the upstanding lug 115 on space bar link member 139 when the space bar 140 is depressed. Under these conditions, the depression of the space bar will rotate stop member 83 counterclockwise and will rotate plate member 53 clockwise, as viewed in Figure 6, releasing the leaf spring 60 in the manner above described, and initiating the operation of the line indicating and bottom margin warning mechanism.

When the top end of the arm 110 is engaged in the groove 124, the line indicating and bottom margin warning mechanism will not be operated.

From the above description, it will be readily apparent that the device is automatically cleared for action when the paper release lever member 23 is moved forwardly in inserting a sheet of paper in the typewriter. After the typist sets the paper in the machine at the proper position with the desired top margin, he begins to type. In accordance with the setting of the rod 101, as above described, the actuation of either any one of the letter keys, the shift key, or the space bar will set the line indicating and bottom margin warning device into operation. From this point on, the advancement of the paper, line by line, will move the block member 51 to the right, step by step, until the desired number of lines are completed. If the roller 22 is then rotated one further step of rotation, the wedge element 82 on stop member 77 engages between block member 51 and leaf spring 60, flexing the leaf spring downwardly and releasing the block member. The tape 45 is then wound up by the spiral spring 49, moving the block member 51 to the left, as viewed in Figure 1, and actuating the bell 85. This provides a warning that the bottom margin of the sheet has been reached. The sheet may then be removed, and a new sheet may be inserted, which clears the device, if necessary, for the next cycle of operation.

While a specific embodiment of an improved line indicating and bottom margin warning device for typewriters has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a line indicating and bottom margin warning device for typewriters, a typewriter carriage, a platen roller journaled on said carriage, a feed screw journaled on said carriage parallel to said roller, a block member slidably mounted on said screw, a movable coupling ele-

ment on said block member normally engaged with the threads of said screw, reel means secured to said carriage, a flexible tape having line indicating markings thereon secured at one end to said reel means and at the other end to said block member, means supporting said tape on said carriage parallel to said feed screw, spring means urging said reel means to wind up said tape thereon, means drivingly coupling said feed screw to said platen roller and being formed and arranged to rotate said screw responsive to rotation of said platen roller, and guide means on the carriage extending parallel to the screw, said guide means being formed and arranged to coact with said block member to guide the block member longitudinally on the screw and to prevent rotation of said block member on said screw.

2. In a line indicating and bottom margin warning device for typewriters, a typewriter carriage, a platen roller journaled on said carriage, a feed screw journaled on said carriage parallel to said roller, a block member slidably mounted on said screw, a movable coupling element on said block member normally engaged with the threads of said screw, reel means secured to said carriage, a flexible tape having line indicating markings thereon secured at one end to said reel means and at the other end to said block member, means supporting said tape on said carriage parallel to said feed screw, spring means urging said reel means to wind up said tape thereon, means drivingly coupling said feed screw to said platen roller and being formed and arranged to rotate said screw responsive to rotation of said platen roller, guide means on the carriage extending parallel to the screw, and a projection on said block member slidably engaged with said guide means, said guide means being formed and arranged to coact with said projection to guide the block member longitudinally on the screw and to prevent rotation of said block member on said screw.

3. In a line indicating and bottom margin warning device for typewriters, a typewriter carriage, a platen roller journaled on said carriage, a feed screw journaled on said carriage parallel to said roller, a block member slidably mounted on said screw, a movable coupling element on said block member normally engaged with the threads of said screw, reel means secured to said carriage, a flexible tape having line indicating markings thereon secured at one end to said reel means and at the other end to said block member, means supporting said tape on said carriage parallel to said feed screw, spring means urging said reel means to wind up said tape thereon, means drivingly coupling said feed screw to said platen roller and being formed and arranged to rotate said screw responsive to rotation of said platen roller, guide means on the carriage extending parallel to the screw, said guide means being formed and arranged to coact with said block member to guide the block member longitudinally on the screw and to prevent rotation of said block member on said screw, a stop member adjustably secured on said carriage in the path of movement of said block member, and cooperating means on the block member and stop member formed and arranged to disengage said coupling element from the threads of the feed screw responsive to movement of the block member to a position adjacent said stop member.

4. In a line indicating and bottom margin warning device for typewriters, a typewriter carriage, a platen roller journaled on said carriage, a feed screw journaled on said carriage parallel to said roller, a block member slidably mounted on said screw, a movable coupling element on said block member normally engaged with the threads of said screw, reel means secured to said carriage, a flexible tape having line indicating markings thereon secured at one end to said reel means and at the other end to said block member, means supporting said tape on said carriage parallel to said feed screw, spring means urging said reel means to wind up said tape thereon,

means drivingly coupling said feed screw to said platen roller and being formed and arranged to rotate said screw responsive to rotation of said platen roller, guide means on the carriage extending parallel to the screw, said guide means being formed and arranged to coact with said block member to guide the block member longitudinally on the screw and to prevent rotation of said block member on said screw, a stop member adjustably mounted on said carriage in the path of movement of said block member, cooperating means on the block member and stop member formed and arranged to disengage said coupling element from the threads of the feed screw responsive to movement of the block member to a position adjacent the stop member, a sounder on the carriage adjacent the path of movement of the block member, and actuating means on the sounder formed and arranged to operate said sounder responsive to movement of the block member therewith in one direction but not in the other direction.

5. In a line indicating and bottom margin warning device for typewriters, a typewriter carriage, a platen roller journaled on said carriage, a feed screw journaled on said carriage parallel to said roller, a block member slidably mounted on said screw, a movable coupling element on said block member normally engaged with the threads of said screw, reel means secured to said carriage, a flexible tape having line indicating markings thereon secured at one end to said reel means and at the other end to said block member, means supporting said tape on said carriage parallel to said feed screw, spring means urging said reel means to wind up said tape thereon, and means drivingly coupling said feed screw to said platen roller and being formed and arranged to rotate said screw responsive to rotation of said platen roller, a plate member mounted on said carriage parallel to said feed screw, said plate member being formed with a slot extending parallel to said feed screw, and a projection on said block member slidably engaged in said slot to guide said block member longitudinally on the screw, and to prevent rotation of said block member on said screw.

6. In a line indicating and bottom margin warning device for typewriters, a typewriter carriage, a platen roller journaled on said carriage, a feed screw journaled on said carriage parallel to said roller, a block member slidably mounted on said screw, a movable coupling element on said block member normally engaged with the threads of said screw, reel means secured to said carriage, a flexible tape having line indicating markings thereon secured at one end to said reel means and at the other end to said block member, means supporting said tape on said carriage parallel to said feed screw, spring means urging said reel means to wind up said tape thereon, means drivingly coupling said feed screw to said platen roller and being formed and arranged to rotate said screw responsive to rotation of said platen roller, a plate member mounted on said carriage parallel to said feed screw, said plate member being formed with a slot extending parallel to said feed screw, a projection on said block member slidably engaged in said slot to guide said block member longitudinally on the screw and to prevent rotation of said block member on said screw, a stop member adjustably mounted on said plate member and extending in the path of movement of said block member, and cooperating means on the block member and stop member formed and arranged to disengage said coupling element from the threads of said screw responsive to movement of the block member to a position adjacent the stop member.

7. In a line indicating and bottom margin warning device for typewriters, a typewriter carriage, a platen roller journaled on said carriage, a feed screw journaled on said carriage parallel to said roller, a block member slidably mounted on said screw, a movable coupling element on said block member normally engaged with the threads of said screw, reel means secured to said carriage, a flexible

tape having line indicating markings thereon secured at one end to said reel means and at the other end to said block member, means supporting said tape on said carriage parallel to said feed screw, spring means urging said reel means to wind up said tape thereon, means drivingly coupling said feed screw to said platen roller and being formed and arranged to rotate said screw responsive to rotation of said platen roller, a plate member mounted on said carriage parallel to said feed screw, said plate member being formed with a slot extending parallel to said feed screw, a projection on said block member slidably engaged in said slot to guide said block member longitudinally on the screw and to prevent rotation of said block member on said screw, a stop member adjustably mounted on said plate member and extending in the path of movement of said block member, cooperating means on the block member and stop member formed and arranged to disengage said coupling element from the threads of said screw responsive to movement of the block member to a position adjacent the stop member, a sounder on the carriage adjacent the path of movement of the block member, and actuating means on the sounder formed and arranged to operate the sounder responsive to movement of the block member therewith in one direction but not in the other direction.

8. In a line indicating and bottom margin warning device for typewriters, a typewriter carriage, a platen roller journaled on said carriage, paper release means on the carriage operatively associated with said roller for releasing the paper with respect to the roller sufficiently to insert a sheet of paper around the roller, a feed screw journaled on said carriage parallel to said roller, a block member slidably mounted on said screw, a movable coupling element on said block member engaged with the threads of said screw, a clearing element movably mounted on the block member and being engageable with the coupling element so as to disengage same from the screw threads responsive to movement of the clearing element, a bar member pivoted to the carriage parallel to the screw and overlying the clearing element, an element on said paper release means normally supporting said bar member and disengaging therefrom responsive to the movement of said paper release means to releasing position, reel means secured to said carriage, a flexible tape having line indicating markings thereon secured at one end to said reel means and at the other end to said block member, means supporting said tape on said carriage parallel to said feed screw, means urging said reel means to wind up the tape thereon, means drivingly coupling said feed screw to said platen roller, and guide means on the carriage formed and arranged to guide said block member longitudinally on said screw.

9. In a line indicating and bottom margin warning device for typewriters, a typewriter carriage, a platen roller journaled on said carriage, paper release means on the carriage operatively associated with said roller for releasing the paper with respect to the roller sufficiently to insert a sheet of paper around the roller, a feed screw journaled on said carriage parallel to said roller, a block member slidably mounted on said screw, a movable coupling element on said block member engaged with the threads of said screw, a clearing element movably mounted on the block member and being engageable with the coupling element so as to disengage same from the screw threads responsive to movement of the clearing element, a bar member pivoted to the carriage parallel to the screw and overlying the clearing element, an element on said paper release means normally supporting said bar member and disengaging therefrom responsive to the movement of said paper release means to releasing position, reel means secured to said carriage, a flexible tape having line indicating markings thereon secured at one end to said reel means and at the other end to said block member, means supporting said tape on said carriage parallel to said feed screw, means urging said reel means to wind up the tape thereon, means drivingly coupling said feed screw to said platen roller, guide means on the carriage formed and arranged to guide

up the tape thereon, means drivingly coupling said feed screw to said platen roller, guide means on the carriage formed and arranged to guide said block member longitudinally on said screw, a stop member adjustably mounted on said carriage in the path of movement of said block member, and cooperating means on the block member and stop member formed and arranged to disengage said coupling element from the screw threads responsive to movement of the block member to a position adjacent said stop member.

10. In a line indicating and bottom margin warning device for typewriters, a typewriter carriage, a platen roller journaled on said carriage, paper release means on the carriage operatively associated with said roller for releasing the paper with respect to the roller sufficiently to insert a sheet of paper around the roller, a feed screw journaled on said carriage parallel to said roller, a block member slidably mounted on said screw, a movable coupling element on said block member engaged with the threads of said screw, a clearing element movably mounted on the block member and being engageable with the coupling element so as to disengage same from the screw threads responsive to movement of the clearing element, a bar member pivoted to the carriage parallel to the screw and overlying the clearing element, an element on said paper release means normally supporting said bar member and disengaging therefrom responsive to the movement of said paper release means to releasing position, reel means secured to said carriage, a flexible tape having line indicating markings thereon secured at one end to said reel means and at the other end to said block member, means supporting said tape on said carriage parallel to said feed screw, means urging said reel means to wind up the tape thereon, means drivingly coupling said feed screw to said platen roller, guide means on the carriage formed and arranged to guide said block member longitudinally on said screw, a stop member adjustably mounted on said carriage in the path of movement of said block member, cooperating means on the block member and stop member formed and arranged to disengage said coupling element from the screw threads responsive to movement of the block member to a position adjacent said stop member, a sounder on the carriage adjacent the path of movement of the block member, and actuating means on the sounder formed and arranged to operate the sounder responsive to movement of the block member therewith when the coupling element is disengaged from the screw threads.

11. In a line indicating and bottom margin warning device for typewriters, a typewriter carriage, a platen roller journaled on said carriage, paper release means on the carriage operatively associated with said roller for releasing the paper with respect to the roller sufficiently to insert a sheet of paper around the roller, a feed screw journaled on said carriage parallel to said roller, a block member slidably mounted on said screw, a movable coupling element on said block member engaged with the threads of said screw, a clearing element movably mounted on the block member and being engageable with the coupling element so as to disengage same from the screw threads responsive to movement of the clearing element, a bar member pivoted to the carriage parallel to the screw and overlying the clearing element, an element on said paper release means normally supporting said bar member and disengaging therefrom responsive to the movement of said paper release means to releasing position, reel means secured to said carriage, a flexible tape having line indicating markings thereon secured at one end to said reel means and at the other end to said block member, means supporting said tape on said carriage parallel to said feed screw, means urging said reel means to wind up the tape thereon, means drivingly coupling said feed screw to said platen roller, guide means on the carriage formed and arranged to guide

10
said block member longitudinally on said screw, a plate member pivoted to said carriage parallel to said feed screw, resilient detent means formed and arranged to retain said coupling element in thread-disengaging position subsequent to the engagement of said clearing element with said coupling element, means on the plate member engageable with said detent means to release the coupling element responsive to rotation of the plate member, and means formed and arranged to rotate said plate member responsive to the operation of one of the operating elements of the typewriter other than the paper release means.

12. In a line indicating and bottom margin warning device for typewriters, a typewriter carriage, a platen roller journaled on said carriage, paper release means on the carriage operatively associated with said roller for releasing the paper with respect to the roller sufficiently to insert a sheet of paper around the roller, a feed screw journaled on said carriage parallel to said roller, a block member slidably mounted on said screw, a movable coupling element on said block member engaged with the threads of said screw, a clearing element movably mounted on said block member and being engageable with the coupling element so as to disengage same from the screw threads responsive to movement of the clearing element, a bar member pivoted to the carriage parallel to the screw and overlying the clearing element, an element on said paper release means normally supporting said bar member and disengaging therefrom responsive to the movement of said paper release means to releasing position, reel means secured to said carriage, a flexible tape having line indicating markings thereon secured at one end to said reel means and at the other end to said block member, means supporting said tape on said carriage parallel to said feed screw, means urging said reel means to wind up the tape thereon, means drivingly coupling said feed screw to said platen roller, guide means on the carriage formed and arranged to guide said block member longitudinally on said screw, a plate member pivoted to said carriage parallel to said feed screw, resilient detent means formed and arranged to retain said coupling element in thread-disengaging position subsequent to the engagement of said clearing element with said coupling element, means on the plate member engageable with said detent means to release the coupling element responsive to rotation of the plate member, means formed and arranged to rotate said plate member responsive to the operation of one of the operating elements of the typewriter other than the paper release means, a stop member adjustably mounted on said carriage in the path of movement of said block member, and cooperating means on the block member and stop member formed and arranged to disengage said coupling element from the screw threads responsive to movement of the block member to a position adjacent said stop member.

13. In a line indicating and bottom margin warning device for typewriters, a typewriter carriage, a platen roller journaled on said carriage, paper release means on the carriage operatively associated with said roller for releasing the paper with respect to the roller sufficiently to insert a sheet of paper around the roller, a feed screw journaled on said carriage parallel to said roller; a block member slidably mounted on said screw, a movable coupling element on said block member engaged with the threads of said screw, a clearing element movably mounted on the block member and being engageable with the coupling element so as to disengage same from the screw threads responsive to movement of the clearing element, a bar member pivoted to the carriage parallel to the screw and overlying the clearing element, an element on said paper release means normally supporting said bar member and disengaging therefrom responsive to the movement of said paper release means to releasing position, reel means secured to said carriage, a flexible tape

having line indicating markings thereon secured at one end to said reel means and at the other end to said block member, means supporting said tape on said carriage parallel to said feed screw, means urging said reel

- 5 means to wind up the tape thereon, means drivingly coupling said feed screw to said platen roller, guide means on the carriage formed and arranged to guide said block member longitudinally on said screw, a plate member pivoted to said carriage parallel to said feed screw, resilient 10 detent means formed and arranged to retain said coupling element in thread-disengaging position subsequent to the engagement of said clearing element with said coupling element, means on the plate member engageable with said detent means to release the coupling element responsive to rotation of the plate member, means formed and arranged to rotate said plate member responsive to the operation of one of the operating elements of the typewriter other than the paper release means, a sounder on the carriage adjacent the path of 15 movement of said block member, and actuating means on the sounder formed and arranged to operate the sounder responsive to movement of the block member therewith when the coupling element is disengaged from the screw threads.

20 14. In a line indicating and bottom margin warning device for typewriters, a typewriter carriage, a platen roller journaled on said carriage, paper release means on the carriage operatively associated with said roller for releasing the paper with respect to the roller sufficient- 25 ly to insert a sheet of paper around the roller, typewriting key elements, a feed screw journaled on said carriage parallel to said roller, a block member slidably mounted on said screw, a movable coupling element on said block member engaged with the threads of said screw, a clearing element movably mounted on the block member and being engageable with the coupling element so as to disengage same from the screw threads responsive to movement of the clearing element, a bar member pivoted to the carriage parallel to the screw and overlying the clearing element, an element on said paper release means normally supporting said bar member and disengaging therefrom responsive to the movement of said paper release means to releasing position, reel means secured to said carriage, a flexible tape having line indicating markings thereon secured at one end to said reel means and at the other end to said block member, means supporting said tape on said carriage parallel to said feed screw, means urging said reel means to wind up said tape thereon, means drivingly coupling said feed screw to said platen roller, guide means on the carriage formed and arranged to guide said block member longitudinally on said screw, a plate member pivoted to said carriage parallel to said feed screw, resilient detent means formed and arranged to retain said coupling element in thread-disengaging position subsequent to the engagement of said clearing element with said coupling element, means on the plate member engageable with said detent means to release the coupling element responsive to rotation of the plate member, a sounder on the carriage adjacent the path of movement of said block member actuating means on the sounder formed and arranged to operate the sounder responsive to movement of the block member therewith when the coupling element is disengaged from the screw threads, a stop member adjustably mounted on said carriage in the path of movement of said block member, cooperating means on the block member and stop member formed and arranged to disengage said coupling element from the screw threads responsive to movement of the block member to a position adjacent said stop member, and means formed and arranged to rotate said plate member responsive to the operation of one of said key elements.

25 15. In a line indicating and bottom margin warning device for typewriters, a typewriter carriage, a platen roller journaled on said carriage, paper release means on the

carriage operatively associated with said roller for releasing the paper with respect to the roller sufficiently to insert a sheet of paper around the roller, a spacer bar, a feed screw journaled on said carriage parallel to said roller, a block member slidably mounted on said screw, a movable coupling element on said block member engaged with the threads of said screw, a clearing element movably mounted on the block member and being engageable with the coupling element so as to disengage same from the screw threads responsive to movement of the clearing element, a bar member pivoted to the carriage parallel to the screw and overlying the clearing element, an element on said paper release means normally supporting said bar member and disengaging therefrom responsive to the movement of said paper release means to releasing position, reel means secured to said carriage, a flexible tape having line indicating markings thereon secured at one end to said reel means and at the other end to said block member, means supporting said tape on said carriage parallel to said feed screw, means urging said reel means to wind up the tape thereon, means driving coupling said feed screw to said platen roller, guide means on the carriage formed and arranged to guide said block member longitudinally on said screw, a plate member pivoted to said carriage parallel to said feed screw, resilient detent means formed and arranged to retain said coupling element in thread-disengaging position subsequent to the engagement of said clearing element with said coupling element, means on the plate member engageable with said detent means to release the coupling element responsive to rotation of the plate member, a sounder on the carriage adjacent the path of movement of said block member, actuating means on the sounder formed and arranged to operate the sounder responsive to movement of the block member therewith when the coupling element is disengaged from the screw threads, a stop member adjustably mounted on said carriage in the path of movement of said block member, cooperating means on the block member and stop member formed and arranged to disengage said coupling element from the screw threads responsive to movement of the block member to a position adjacent said stop member, and means formed and arranged to rotate said plate member responsive to the operation of said spacer bar.

16. In a line indicating and bottom margin warning device for typewriters, a typewriter carriage, a platen roller journaled on said carriage, paper release means on the carriage operatively associated with said roller for releasing the paper with respect to the roller sufficiently to insert a sheet of paper around the roller, a shift key member, a feed screw journaled on said carriage parallel to said roller, a block member slidably mounted on said screw, a movable coupling element on said block member engaged with the threads of said screw, a clearing element movably mounted on the block member and being engageable with the coupling element so as to disengage same from the screw threads responsive to movement of the clearing element, a bar member pivoted to the carriage parallel to the screw and overlying the clearing element, an element on said paper release means normally supporting said bar member and disengaging therefrom responsive to the movement of said paper release means to releasing position, reel means secured to said carriage, a flexible tape having line indicating markings thereon secured at one end to said reel means and at the other end to said block member, means supporting said tape on said carriage parallel to said feed screw, means urging said reel means to wind up the tape thereon, means drivingly coupling said feed screw to said platen roller, guide means on the carriage formed and arranged to guide said block member longitudinally on said screw, a plate member pivoted to said carriage parallel to said feed screw, resilient detent means formed and arranged to retain said coupling element in thread-disengaging position subsequent to the engagement of said clearing element with said coupling element, means on the plate member engageable with

5 said detent means to release the coupling element responsive to rotation of the plate member, a sounder on the carriage adjacent the path of movement of said block member, actuating means on the sounder formed and arranged to operate the sounder responsive to movement of the block member therewith when the coupling element is disengaged from the screw threads, a stop member adjustably mounted on said carriage in the path of movement of said block member, cooperating means on the block member and stop member formed and arranged to disengage said coupling element from the screw threads responsive to movement of the block member to a position adjacent said stop member, and means formed and arranged to rotate said plate member responsive to the operation of said shift key member.

10 17. In a line indicating and bottom margin warning device for typewriters, a typewriter carriage, a platen roller journaled on said carriage, feed means journaled on said carriage, a block member slidably mounted on said feed means, reel means secured to said carriage, a flexible line indicating tape secured at one end to said reel means and at the other end to said block member, means supporting said tape on said carriage, means urging said reel means to wind up the tape thereon, means drivingly coupling said feed means to said platen roller and being formed and arranged to operate said feed means responsive to the rotation of said platen roller, indicating means on said tape, and means to move said block member and said tape forwardly on the feed means responsive to the rotation of said platen roller.

15 18. In a line indicating and bottom margin warning device for typewriters, a typewriter carriage, a platen roller journaled on said carriage, feed means journaled on said carriage, a block member slidably mounted on said feed means, reel means secured to said carriage, a flexible line indicating tape secured at one end to the reel means and at the other end to said block member, means supporting said tape on said carriage, means urging said reel means to wind up the tape thereon, means drivingly coupling said feed means to said platen roller and being formed and arranged to operate said feed means responsive to the rotation of said platen roller, indicating means on said tape, means to move said block member and said tape forwardly on the feed means responsive to the rotation of said platen roller, a stop member adjustably secured on said carriage in the path of movement of said block member, and means whereby said block member and said stop member coact when said block member reaches a position adjacent said stop member to release said block member and allow said block member to be moved back by said reel means to its starting position.

20 19. In a line indicating and bottom margin warning device for typewriters, a typewriter carriage, a platen roller journaled on said carriage, feed means journaled on said carriage, a block member slidably mounted on said feed means, reel means secured to said carriage, a flexible line indicating tape secured at one end to said reel means and at the other end to said block member, means supporting said tape on said carriage, means urging said reel means to wind up the tape thereon, means drivingly coupling said feed means to said platen roller and being formed and arranged to operate said feed means responsive to the rotation of said platen roller, indicating means on said tape, means to move said block member and said tape forwardly on the feed means responsive to the rotation of said platen roller, a stop member adjustably secured on said carriage in the path of movement of said block member, means whereby the block member and said stop member coact when said block member reaches a position adjacent said stop member to release said block member and allow said block member to be pulled back by said reel means to its starting position, a sounder on the carriage adjacent the path of movement of said block member, and actuating means on the sounder formed and arranged to operate said sounder responsive

17

to movement of said block member therewith in one direction but not in the other direction.

20. In combination with the structure of claim 19, paper releasing means on the carriage operatively associated with said roller for releasing the paper with respect to the roller sufficiently to insert a sheet of paper around the roller, and a clearing mechanism operated by said releasing means formed and arranged to allow said block member to be pulled back by said reel means responsive to the operation of said paper releasing means.

21. In combination with the structure of claim 20, a shift key, and means formed and arranged to initiate the advance of said block member on said feed means responsive to the operation of said shift key.

18

22. In combination with the structure of claim 20, letter keying elements and means formed and arranged to initiate the advance of said block member on said feed means responsive to the operation of any of said keying elements.

23. In combination with the structure of claim 20, a space bar, and means formed and arranged to initiate the advance of the block member on said feed means responsive to the operation of said space bar.
